ROTARY CARD HOLDER

George Browning, San Diego, Calif.

Application January 10, 1950, Serial No. 7,140

Term of patent 3½ years

(Cl. D34—13)

To all whom it may concern:

Be it known that I, George Browning, a citizen of the United States of America, residing at San Diego, in the county of San Diego and State of California, have invented a new, original, and ornamental Design for Rotary Card Holder, of which the following is a specification, reference being had to the accompanying drawings, forming a part thereof.

Fig. 1 is a perspective view of a rotary card holder, showing my new design; and Fig. 2 is a sectional view, taken from the line 2—2 of Fig. 1.

I claim:

The ornamental design for a rotary card holder, substantially as shown.

GEORGE BROWNING.
